UNITED STATES PATENT OFFICE.

CLARENCE R. MARTINEAU, OF ALBANY, NEW YORK, ASSIGNOR TO I. P. C. UNIVERSAL CORPORATION, OF ALBANY, NEW YORK, A CORPORATION OF NEW YORK.

SEAL FOR RAILWAY CARS, ETC.

Application filed August 8, 1924. Serial No. 730,805.

This invention relates to seals for use upon car doors and in other places.

An object of the invention is to provide a device of simple and inexpensive construction, which can be easily and economically manufactured, and quickly and easily operated and conveniently inspected, and to provide that the seal cannot be unlocked or tampered with without such fact at once becoming evident.

To these ends, a shackle in the form of a flexible band or strap of soft metal is welded at one end to a head-piece of hardened steel or other brittle metal. In this head is provided an eye through which the other or free end of the attached strap is thrust, this free end interlocking with the eye, and the head-piece being then folded down into notches formed in the top edges of the strap, which thus becomes permanently interlocked with the head-piece; while the latter, due to its brittle nature, is not unfoldable, and absolute locking or sealing is assured.

Other features and advantages will hereinafter appear.

In the accompanying drawings,

Figure 1 is a front and side elevation of the hardened steel head having a foldable integral flap.

Figure 2 is a front and side elevation of the soft metal strap with a pendent tag thereon.

Figure 3 is a front elevation of another form of head having the foldable flap divided into two portions.

Figure 4 is still another form of the head with the foldable flap separated at one side of the head.

Figure 5 is a front elevation of the improved seal ready for use.

Figure 6 is a view of the strap folded in collar form and locked at its free end to the head.

Figure 7 is an elevation of the seal in locked or sealed condition, and sealing a lock on a railway car, the strap being turned back to form a collar, as at Figure 6.

Figure 8 is a side elevation of the device seen at Figure 7.

Figure 9 is a view similar to Figure 5, but showing the pendent tag omitted from the strap and from the head.

Figure 10 is a view similar to Figure 9,

but showing the strap as doubled or folded forwardly upon itself and inserted in the eye in the head ready for being locked.

The seal comprises a head 10 and a strap 11. The head is a plate of hardened steel, which is very brittle, and is welded to the end of the strap, as at 12. A portion of the head is designed to fold down over the lapped ends of the strap, as will presently be explained, to lock said ends against separation; and the brittleness of the steel head makes it impossible for it to be opened up, and hence the strap cannot be released and removed from the lock which it seals. Attempt to unfold the head results in breaking the same, or at least injuring it and showing that it has been tampered with.

The strap is of soft metal, to take the imprint of a lettering or other tool.

The strap may be of any desired length, and, during the process of manufacture, it is drawn through an eye 13, which is pressed out from the brittle head 10 sufficiently to accommodate said strap. In forming said eye, spaced narrow holes or slits 14, 15 are punched in the head, and the eye 13 is pressed out, thus leaving a narrow opening through which the strap can be pulled, the strap fitting rather closely in the opening. This end of the strap is preferably formed with a tag portion 16, which underlies the eye 13, Figure 5, the tag portion being separated from the body of the strap by a slit 17, to permit the proper assemblage of strap and head.

The eye 13 is formed on the head below a flap 18, which is designed to be folded down upon an axis which is about coincident with the top of the eye 13; and at this fold point or region the head 10 is provided with deep or heavy fold-scores 19, which may be pressed in the metal.

In assembling the parts, preparatory to welding, the strap is drawn toward the left through the eye 13, until it reaches the position at Figure 5, and at that time the strap and head are partly locked together by means of a notch 20, formed in the under edge of the strap at its right-hand end, and fitting upon or interlocking with the pressed-out panel which forms the eye 13. This notch permits the strap to settle in the eye and effect such interlock. The strap and head are now welded together in this

position, as at 12. The welding extends down from the top edge of the strap or band, welding the band to the head, but permitting the latter to be folded down after 5 the welding.

In use, the strap may be passed through the lock or article 21, and then the strap may be looped by thrusting the free end thereof through the eye 13, which is sufficiently open to accommodate the same, although the strap fills up the eye. The strap is located endwise in the eye by means of a notch 22 which is formed in the lower end of the strap or band, and which interlocks with the bottom of the panel or eye 13, so that both ends of the strap interlock with said panel in substantially the same manner.

The upper edges of the strap ends, where they are superposed, are now coincident; and the flap 18 formed upon the brittle head 10 is folded down to effect the sealing. The head folds down upon the score lines 19 and into corresponding notches 23 and 24 that are formed in the upper edges of the strap at its ends in registry with each other, the registration being effected by the notches 20 and 22. The flap 18 folds right down into these notches, as will be understood from Figures 5 and 7, and thereby locks the end 25 of the strap in the eye; said flap being, as already explained, incapable of opening out to release the strap.

To provide for interlocking, there is formed in the head a U-shaped slit 26, the lower edge of which defines the top 27 of the head after folding, and the upper edge of which defines the lower edge of the body portion of the flap 18, this slit embracing the upper part of the eye portion of the head; and hence it results that the flap may be folded down into the notches 23 and 24 formed in the band, while said band is threaded closely into said eye 13 in the head. In other words, the flap comprises side portions or leaves 28 which are relatively narrow, so as to be easily bendable, and they join the main portion of the head below the top of the eye which contains the band, thus permitting said side portions to be forced down into the notch 24 in the top edge of the band to lock or seal the same, and also to hold the bottom notches 20, 22 in permanent interlocking engagement with the eye or panel 13. When the flap 18 is folded down, its opening 26 gives a view of the eye and the strap therein, and shows clearly whether the seal is unmolested. To this end, the flap 18 may in some cases have a large interior notch or cutaway 29, so that substantially the entire eye may be visible. The notches 30 in the side of the folded-down part of the head are to leave exposed more of the underlying end of the seal, to disclose whether the seal has been tampered 65 with or not. At the same time the flap

leaves exposed the eye with the strap locked therein. The notch in the top edge of the strap absolutely insures the locking.

The free end of the strap has an extended tag portion 31^a, upon which may be impressed characters 31, which facilitates instant reading, because this part stands out prominently from the main portion of the seal.

The drop tag portion 16 fills a long-felt want, when it is desired to place the imprint of a hand-tool upon the seal.

The extended left-hand end of the strap, constituting the tag portion, need not be used in its entirety for imprint purposes when the drop tag portion is used, neither is it necessary in all cases to use the drop tag portion when the extended tag portion is used. Where a double check is desired, both tag portions are valuable. It is usually the case that in the right-hand end of the seal the initials of the railroad are also stamped at 32. Anybody tampering with the seal would be likely to cut it, and afterwards to push it in to the left, and then secure it, so that it would not be readily noticed that the seal had been tampered with. But in that case a letter 31 or a portion thereof would appear boldly through a notch 30 in the folded-down flap, instead of being partly concealed by the flap, and this would indicate that the seal had been tampered with.

The seal may be used as either a loop or a collar, to accommodate itself to the different styles of car-door fasteners. If used as a collar, the strap is bent around the opposite way to form the collar, as at Figure 6, and its end is thrust into the eye, as at Figure 7.

If it is not desirable to use a tool, the tag portion 16 of the strap may be omitted, and the end of the strap is welded to the head.

This tag, when used, is formed on the end of the strap, and is therefore soft.

The cost of this device is very small, as it is mainly simple press work.

In order to insure absolute locking, it is only necessary to pass the free end of the strap through the eye until the recess on the strap engages with the eye, and then press down the flap tightly, thus completing the locking operation. Unlocking or tampering with the seal makes itself evident. If the scored head, which is specially treated, should be bent back, for the purpose of releasing the free end of the strap, a break would be made at one or more of the scores, which are deeply pressed into the metal, and the flap would break away from the head. Moreover, the sight-openings in the flap 125 would expose upon inspection any attempt at tampering.

At Figure 3, the foldable flap is divided into two portions by means of a slit 33. At Figure 4, one of the side leaves of the single

flap is scored and the other is horizontally slit at 34 to facilitate folding and bending the device 35, and thus making detection of injury easier.

5 Variations may be resorted to within the scope of the invention, and portions of the improvements may be used without others.

Having thus described my invention, I claim:

10 1. A seal comprising a flexible strap of soft metal formed with edge notches, and a head of hard and brittle metal welded to one end thereof and having an eye receiving and interlocking with the free end of the strap, said head foldable into the notches formed in the strap and interlocking with the strap.

20 2. A seal comprising a flexible strap of soft metal formed with edge notches between its ends, the notches being near the ends of the strap, and a head of hard and brittle metal welded to one end thereof and having an eye receiving and interlocking with the free end of the strap, said head foldable into said notches formed in the strap and interlocking with the strap, said head in the form of a plate, and said eye comprising a panel pressed out from said plate, and said head having a cut-away portion to receive the eye-panel when the head is folded.

30 3. A seal comprising a flexible strap of soft metal formed with notches between the ends thereof, said notches in the same edge of the strap and near said ends, and a head of hard and brittle metal welded to one end thereof and having an eye receiving and interlocking with the free end of the strap, said head foldable into said notches formed in the strap and interlocking with the strap, said head in the form of a plate, said plate formed with a pair of spaced slits defining a panel, and the panel pressed out from the plate to form the eye and admit the strap.

40 4. A seal comprising a flexible strap of soft metal formed with separated notches in its top edge, and a head of hard and brittle metal welded to one end thereof and having an eye receiving and interlocking with the free end of the strap, said head foldable into said notches formed in the strap when looped and interlocking with the strap, said head in the form of a plate, and said eye comprising a panel pressed out from said plate, said strap having a pendent tag portion overlying said plate beneath said eye and partly separated from the strap by a slit.

50 5. A seal comprising a flexible strap of soft metal formed with a notch in its edge, and a head of hard and brittle metal welded thereto at one end and having an eye receiving the free end of the strap and interlocking with said free end, said head having at its top a flap above said eye and foldable

down into said notch formed in the strap and interlocking with the strap, said head in the form of a plate, and said eye comprising a panel pressed out from said plate.

6. A seal comprising a flexible strap of soft metal formed with a notch in its edge, and a head of hard and brittle metal welded thereto at one end and having an eye receiving the free end of the strap and interlocking with said free end, said head having at its top a flap above said eye and foldable down into said notch formed in the strap and interlocking with the strap, said head in the form of a plate, and said eye comprising a panel pressed out from said plate, 75 said flap foldable down upon an axis about coincident with the top of the eye.

7. A seal comprising a flexible strap of soft metal, having notches formed in its upper edge, and a head of hard and brittle metal welded to one end thereof and having an eye receiving the free end of the strap, said head foldable into said notches formed in the strap and interlocking with the strap, said strap also having on its under edge a notch which interlocks with the bottom portion of the eye, the strap being welded to the eye with said under notch in interlocked position.

8. A seal comprising a flexible strap of soft metal, having edge notches formed therein and a head of hard and brittle metal welded to one end thereof and having an eye receiving the free end of the strap, said head foldable into said notches formed in the strap and interlocking with the strap, the free end of said strap insertable in said eye and filling the same and having a notch to interlock with the bottom portion of said eye.

9. A seal comprising a flexible strap of soft metal, and a head of hard and brittle metal welded to one end thereof and having an eye receiving the free end of the strap, the free end of said strap insertable in said eye and filling the same, the fixed and free portions of said strap having notches located near the ends of the strap, said notches coinciding, and said head being foldable down into said notches to constitute interlocking means between the strap and head.

10. A seal comprising a flexible strap of soft metal, having notches formed in its edge, and a head of hard and brittle metal welded to one end thereof and having an eye receiving and interlocking with the free end of the strap, a U-shaped slit being formed in said head and defining the top of the eye portion of the head and also defining the lower edge of the folded portion of the head, the head folding down into said notches formed in the strap and interlocking with and holding the latter closely to the eye in the head.

11. A seal comprising a flexible strap of soft metal, having notches in its top edge,

and a head of hard and brittle metal welded to one end thereof and having an eye receiving and interlocking with the free end of the strap, a U-shaped slit being formed in said head and defining the top of the eye portion of the head and also defining the lower edge of the folded portion of the head, said flap comprising side leaves which are relatively narrow, and which join the main portion of the head below the top of said eye, said side portions bendable down into said notches in the top edges of the strap to lock the same.

12. A seal comprising a flexible strap of soft metal, having a top edge notch, and a head of hard and brittle metal welded to one end thereof and having an eye receiving the free end of the strap, said head folded into said notch formed in the strap and interlocking 20 with the strap, said strap also having on its under edge a notch which interlocks with the bottom portion of the eye, the strap being welded to the eye with said under notch in interlocked position, said fold also holding the bottom notch in permanent interlocking engagement with the bottom part of the eye.

13. A seal comprising a flexible strap of soft metal, having edge notches and a head 30 of hard and brittle metal welded thereto at one end and having an eye receiving the free end of the strap and interlocking with said free end, said head having at its top a flap above said eye and foldable down into said 35 notches formed in the strap and interlocking with the strap, said head in the form of a plate, and said eye comprising a panel pressed out from said plate, said flap foldable down upon an axis about coincident 40 with the top of the eye, said flap having a large interior cutaway rendering the main portion of the eye visible.

14. A seal comprising a flexible strap of soft metal, having notches, and a head of 45 hard and brittle metal welded thereto at one end and having an eye receiving the free end of the strap and interlocking with said free

end, said head having at its top a flap above said eye and foldable down into said notches formed in the strap and interlocking with the strap, said head in the form of a plate, and said eye comprising a panel pressed out from said plate, said flap foldable down upon an axis about coincident with the top of the eye, said flap having a large interior cutaway 55 rendering the main portion of the eye visible, and also having side notches to leave exposed underlying portions of the seal.

15. A seal comprising a flexible strap of soft metal, having notches therein and a 60 head of hard and brittle metal welded to one end thereof and having an eye receiving and interlocking with the free end of the strap, said head foldable into said notches formed in the strap and interlocking with the strap, 65 the free end of the strap having an extended tag portion.

16. A seal comprising a flexible strap of soft metal, having notches therein and a 70 head of hard and brittle metal welded thereto at one end and having an eye receiving the free end of the strap and interlocking with said free end, said head having at its 75 top a flap above said eye and foldable down into said notches formed in the strap and interlocking with the strap, said head in the form of a plate, and said eye comprising a panel pressed out from said plate, said flap divided into two portions by means of a slit.

17. A seal comprising a flexible strap of soft metal, having notches therein, and a 80 head of hard and brittle metal welded thereto at one end and having an eye receiving the free end of the strap and interlocking with said free end, said head having at its 85 top a flap above said eye and foldable down into said notches in the strap and interlocking with the strap, said head in the form of a plate, and said eye comprising a panel pressed out from said plate, one of the side 90 leaves of said flap being scored and the other being horizontally slit.

CLARENCE R. MARTINEAU.
